United States Patent

Des. 239,368
Patented Mar. 30, 1976

239,368

BOTTLE OR SIMILAR ARTICLE

John W. McDonald, Kansas City, Mo., assignor to Ethyl
Development Corporation, Kansas City, Mo.

Filed Mar. 25, 1974, Ser. No. 454,240

Term of patent 14 years

Int. Cl. D9—01

U.S. Cl. D9—143

FIG. 2.

FIG. 1.

FIG. 3.

FIG. 4.

FIG. 5.

FIG. 6.

FIG. 7.

FIG. 1 is a front elevational view of a bottle embodying my new design;

FIG. 2 is a top plan view thereof;

FIG. 3 is a bottom plan view thereof;

FIG. 4 is a side elevational view thereof;

FIG. 5 is a cross-sectional view of FIG. 1 along line 5—5;

FIG. 6 is a cross-sectional view of FIG. 1 along line 6—6; and

FIG. 7 is a cross-sectional view of FIG. 1 along line 7—7.

I claim:

The ornamental design for a bottle or similar article, substantially as shown.
